UNITED STATES PATENT OFFICE.

JOSEPH M. DIDERO, OF LORAIN, OHIO.

DESIGN FOR AN AX-BLADE.

SPECIFICATION forming part of Design No. 20,814, dated June 2, 1891.

Application filed April 21, 1891. Serial No. 389,841. Term of patent 14 years.

To all whom it may concern:

Be it known that I, JOSEPH M. DIDERO, a citizen of the United States, residing at Lorain, in the county of Lorain and State of Ohio, have invented and produced a new and original Design for Ax-Blades, of which the following is a specification, reference being had to the accompanying drawing, forming a part thereof, which represents by a perspective view an ax-blade embodying my design.

The upper boundary-line a of the blade is curved from the head A to the cutting-edge and imparts to the upper edge of the blade a convexed appearance. The lower boundary-line a' is shorter than the upper line a and extends diagonally or at an inclination down-

ward from the head, meeting a line a^2 , which is curved slightly outward and defines the cutting-edge. The line a^2 also meets the outer extremity of the upper marginal line a . The upper and lower marginal lines so meet the line defining the cutting-edge of the ax that the corners a^3 , formed by the junction of the lines, are practically right angular. 20

I claim—

A design for an ax-blade, substantially as herein shown and described. 25

JOSEPH M. DIDERO.
